UNITED STATES PATENT OFFICE.

JOSEPH MCKAY, OF TROY, NEW YORK, ASSIGNOR, BY MESNE ASSIGNMENTS, TO HALL, HARTWELL & CO., OF TROY, NEW YORK, A FIRM CONSISTING OF WILLIAM L. HALL, JOSEPH MCKAY, BURTON K. WOODWARD, CHARLES E. HARTWELL, JOHN P. SCHAD, AND JAMES M. AUGUR.

FOLD-COLLAR.

1,070,977.

Specification of Letters Patent.

Patented Aug. 19, 1913.

Continuation of application Serial No. 418,438, filed February 29, 1908. This application filed January 14, 1910. Serial No. 538,099.

To all whom it may concern:

Be it known that I, JOSEPH MCKAY, a citizen of the United States, residing at Troy, county of Rensselaer, and State of New York, have invented certain new and useful Improvements in Fold-Collars, of which the following is a specification.

The invention relates to such improvements and consists of the novel construction and combination of parts hereinafter described and subsequently claimed.

This application is a continuation of my application No. 418,438 filed Feb. 29, 1908.

Reference may be had to the accompanying drawings, and the reference characters marked thereon, which form a part of this specification. Similar characters refer to similar parts in the several figures therein.

Figure 1 of the drawings is a plan view 20 of a fold-collar extended, with the collar-top uppermost, illustrating one form of my invention. Fig. 2 is a vertical cross-section of the same, taken on the broken line 2—2 in Fig. 1, drawn on an exaggerated scale.

The invention relates more particularly to the style of fold-collar which has a high upright band and a top folded over upon the band, and adapted particularly at the back and sides of the collar to occupy a position substantially parallel with the band. Such collars are adapted to receive between the top and the band the necktie or scarf of the wearer. In tying or adjusting a scarf or necktie worn with a collar of this type, much difficulty is experienced by reason of the catching of the tie on or under the head of the collar-button at the back of the collar, which prevents the band of the tie from moving freely in the space 30 between the band and top of the collar in response to the pull upon the end or ends of the tie in adjusting the same.

The principal objects of the present invention are to shield the head of the collar-button from contact or engagement with the band or tie, and thereby to facilitate the sliding of the band of the tie in response to the pull upon its respective ends; and to facilitate separation of the shield-member 40 from the back-buttonhole member after laundrying.

In the preferred form of my invention I accomplish these objects by applying to the outer side of the band of the collar, at the back thereof, a tab or shield, the lower end 55 of which is free from the band and adapted to hang loosely down over the back-button-hole in the band, in position to cover the head of the back collar-button, with its free end depending below the lower edge of the 60 band.

Referring to Fig. 1 of the drawings, wherein the invention is shown in preferred form, 1, represents the band and, 2, the top of the collar, each being formed of three 65 plies of fabric, the plies of the top being inserted between the inturned edges of the plies of the band, along the top of the band, and secured by stitching, 3, in the usual manner. The band is provided with the 70 end-buttonholes, 4, and the back-buttonhole, 5, in the usual manner.

To provide a shield for the rear button-hole, a tab, 6, formed of two plies of fabric is applied to the outer side of the band, at 75 the back or middle thereof, the top-edges of said plies being inserted between the band-plies and secured by means of the stitching, 3, while the body of said tab is secured to the body of the band by the stitching, 7, along 80 the side-edges of the tab, and by a horizontal row of stitching, 8, which connects an intermediate portion of the tab with the body of the band along a line extending longitudinally of the band slightly above the 85 rear buttonhole. The lower end, 9, of the tab is thus left free from the band and hangs down over the rear-buttonhole in the band in position to cover the head of the rear 90 collar-button inserted through the rear buttonhole, 5, of the band, with its free end depending below the lower edge of the band. In laundrying collars of this kind, it is found difficult, and in custom laundries practically impossible, to prevent the buttonhole-member and the shield-member 95 from adhering to each other as a result of the starching and ironing processes. By having the tab depend below the lower edge of the band, as described, it is comparatively 100 easy for the user to pull the tab free from the band up to the line of stitching, 8, by

grasping in one hand the free depending edge of the tab, and in the other the lower edge of the band just at one side of the tab.

In using the collar, the scarf or necktie is inserted between the top of the collar and the tab, 9, at the rear, and between the top and band of the collar at the sides and front thereof, so that the tie is protected by the tab-end, 9, from contact or engagement with the head of the rear collar-button, and the band of the tie is permitted to slide freely in response to the pull upon its respective ends.

Much of the difficulty experienced in wearing a band-tie with high fold-collars is due to the fact that the scarf or tie slips up over the head of the rear collar-button and then down between the head and the body of the band. By providing the collar with a tab or shield attached to the band above the rear buttonhole and adapted to hang down over the same, it is impossible for the band of the scarf to work in between the head of the rear collar-button and the body of the band.

While in the preferred form of the invention I employ, as a means for attaching the tab to the band, a horizontal line of stitching extending entirely across the tab above the back buttonhole in the band, I do not wish to be limited to this specific feature, as it will be apparent that for certain purposes of the invention the particular manner of attachment of the tab is immaterial so long as it is connected with the band at a point above the horizontal line of the buttonhole so as to maintain the top of the tab well above the head of the back button in use, and so long as the manner of attaching the tab leaves the tab with a freely hanging

lower end-portion which can be readily separated from the band to afford access to the back buttonhole.

What I claim as new and desire to secure by Letters Patent is—

1. The combination with a collar comprising a neck-band and a turn-down portion, said neck-band having the usual back buttonhole; of a separate buttonhole-covering shield located between the turn-down and neck-band portions and attached to the outer side of said neck-band at a point above the horizontal line of said back buttonhole, said shield having a free end depending below its point of attachment to said band-portion. 55

2. The combination with a collar comprising a neck-band and a turn-down portion, said neck-band having the usual back buttonhole; of a separate buttonhole-covering shield located between the turn-down and neck-band portions and attached to the outer side of said neck-band by a horizontal line of stitching above said back buttonhole, said shield being free from said band from said horizontal line of stitching to its lower end. 60

3. The combination with a collar comprising a neck-band and a turn-down portion, said neck-band having the usual back buttonhole; of a separate buttonhole-covering shield located between the turn-down and neck-band portions and attached to the outer side of the neck-band, said shield having a free lower end depending below the lower edge of the neck-band. 70

In testimony whereof, I have hereunto set my hand this 13th day of January, 1913.

JOSEPH MCKAY.

Correction in Letters Patent No. 1,070,977.

It is hereby certified that in Letters Patent No. 1,070,977, granted August 19, 1913, upon the application of Joseph McKay, of Troy, New York, for an improvement in "Fold-Collars," the names of the members of the firm of Hall, Hartwell & Co. were erroneously given in the grant and in the heading of the printed specification as "William L. Hall, Joseph McKay, Burton K. Woodward, Charles E. Hartwell, John P. Schad, and James M. Augur," whereas they should have been given as *William L. Hall, Joseph McKay, and Burton K. Woodward*, as shown by the records of assignments of this office; and that the said Letters Patent should be read with this correction therein that the same may conform to the record of the case in the Patent Office.

Signed and sealed this 23d day of September, A. D., 1913.
